CLAIM

The ornamental design for a fastener, as shown and described.

DESCRIPTION

FIG. 1 is an enlarged exploded perspective view of a front, top, and right side of a fastener, the exploded perspective view of the rear, top, and left side being identical thereto; FIG. 2 is a perspective view of a front, top, and right side of the fastener of FIG. 1, the perspective view of the rear, top, and right side being a mirror image thereof; FIG. 3 is a front elevational view thereof; and, FIG. 4 is another environmental front elevational view thereof.

The fastener of FIGS. 1-4 includes portions illustrated in dash-dot-dot lines for the purpose of illustrating unclaimed subject matter that forms no part of the claimed design. FIGS. 2-4 include additional dash-dot-dot lines that are included for the purpose of illustrating unclaimed environmental structure, which forms no part of the claimed design.
